ABSTRACT OF THE DISCLOSURE

An oscillating magnet moves along radial armature portions of a wheel which are slanted to the plane of oscillation and to the path of the magnet to form air gaps of different width so that the wheel is stepwise rotated while the magnetic coupling between the magnet and an armature portion is established at the beginning of a stroke and interrupted at the end of the stroke where the air gap is widest, whereupon the next following armature portion is magnetically coupled with the magnet.

BACKGROUND OF THE INVENTION

The invention relates to a magnetic device for transforming an oscillatory motion into a rotary motion of the type used for driving clockworks, particularly of electric watches. The device may be used for driving the balance wheel of a watch, or for magnetically controlling the escapement mechanism of spring driven watches and clocks.

A watch using an oscillating tuning fork with magnetically controlled escapement wheel is known in which the wheel has inner and outer circular rows of teeth consisting of a magnetizable material. A disadvantage of the known constructions is that they are not self-starting. Since the oscillator magnet produces a torque in both directions of rotation of the wheel, the wheel has no preferred direction of rotation, so that it has to be started until reaching a number of revolutions synchronous with the frequency of the oscillator magnet.

Another magnetic escapement device is known in which adjacent portions of armature portions of the wheel have different dimensions so that the magnetic force has a greater effect in one direction of rotation than in the other. However, the difference between the magnetic forces acting in opposite directions is so small that the mechanism can only be started without any load. Since the driven pointers produce a reverse torque, the available force differences are hardly sufficient for self-starting. It is even possible that the reverse torque of the pointers pushes the wheel back due to the fact that the magnetic force decreases with a square of the distance.

In another construction of the prior art, which is designed for mechanically oscillating drive elements, the wheel has coupling teeth which are so shaped as to favor one direction of rotation. Due to the low difference between the opposing forces, the device has a very low efficiency.

SUMMARY OF THE INVENTION

It is one object of the invention to provide a self-starting magnetic device for stepwise driving a wheel.

Another object of the invention is to provide a magnetic device for transforming an oscillatory motion into rotary motion which produces sufficient torque to drive a large clock for example a wall clock without substantially dampening the oscillation of the oscillatory drive means.

Another object of the invention is to provide a magnetic

2

device for transforming an oscillatory motion into a rotary motion which operates at high efficiency, and with great reliability.

In contrast to the prior art, the present invention relies on air gaps of varying width for obtaining different magnetic forces acting in opposite directions of rotation of the wheel. Since the magnetic force is proportional to the square of the distance, a variation of the air gap is very effective. When the air gap is increased, the magnetic coupling force between the oscillator magnet and the armature portion of the wheel is reduced, and when the air gap is wide enough, the magnetic coupling is interrupted so that the oscillatory magnet can perform a return stroke without any magnetic effect on the driven wheel which is consequently rotated only in one direction, and easily starts.

In accordance with the invention, one or two oscillatory magnets, and magnetizable armature portions of the driven wheel are arranged so that the air gap between the same varies its width along the path of movement of the oscillatory magnet in such a manner that during rotation of the wheel in one direction of rotation, the magnetic coupling of the oscillatory magnet with the respective armature portion magnetically coupled therewith, is reduced, while it again increases for the next following armature portion.

One embodiment of the invention comprises oscillatory means including a magnet means swinging in a first plane along a path, the path being preferably part-circular; and a driven wheel having a circumferential row of equidistant temporarily magnetizable armature means.

The wheel has a plurality of positions in which successive armature means are located in the region of the path of the magnet means defining a first angle with the path, whereby the magnetic force between the magnet means and the respective armature means causes stepwise turning of the wheel in one direction of rotation at least during a working stroke of the magnet means.

The armature means also define a second angle with the plane of oscillation of the magnet means, so that during rotation of the wheel in one direction of rotation, a magnetic coupling force between the magnet means and the respective cooperating armature means is established at the beginning of a stroke, decreases during the stroke due to the widening of the air gap, and is interrupted at the end of the stroke whereupon the magnet means magnetically couples with the next following armature means.

In one embodiment of the invention there is only one oscillating magnet provided which during opposite strokes cooperates with two armature portions of the respective armature means. Each armature means includes a first armature portion, a second armature portion and a third armature portion connected with the first and second armature portions. The first and second armature portions converge in outward direction and being connected at the extremities thereof by the third armature portion. The armature portions form a circular zig-zag shaped magnetizable structure about the center portion of the wheel, which preferably includes spokes to which the inner ends of the first armature portions are connected. The magnet moves during each stroke substantially along a first armature portion and during the following opposite substantially along the second armature portion, and since the same define different angles with the path of the magnet, the wheel is driven. The first armature portions define small angles with the plane of oscillation of the magnet between the reversing points of the oscillation of the magnet, while the third armature portion, which connects the first and second armature portions is steeply slanted in opposite direction in relation to the plane of oscillation.

For an oscillatory movement of the magnet means at a frequency between 15 and 40 hertz, and with an ampli-

tude between 10° and 30°, the magnetic coupling between the magnet means and the annular zigzag-shaped or sinusoidal armature structure is maintained so that the wheel is continuously rotated, and stopped after each step. The flat slant of the first and second armature portions has the effect that the magnetic coupling is increased during an oscillatory stroke in one direction and decreased during the oscillatory stroke during the opposite direction. Since at the reversing points, the third armature portion having an opposite steep slant is coupled with the magnet means, the coupling of the magnet means with the next following armature portion prevails, so that the wheel is forced to rotate in one direction of rotation only.

The arrangement has the advantage that the wheel can be started without additional starting energy and in a preferred direction of rotation. Furthermore, a wheel has the effect of stabilizing the amplitude of oscillation of the oscillatory magnet, in the event that the same swings beyond the armature structure in radial direction in relation to the wheel, since a reduction of the coupling force between the magnet means and the armature portions prevents an increase of the amplitude of oscillation of the magnet means.

The spokes of the wheel are located outside of range of the amplitude of oscillation of the magnet means so that they are not magnetically coupled with the same.

In another embodiment of the invention, the oscillatory means include two magnets which are spaced along the part-circular path along which they swing. Each armature means includes two armature portions spaced in circumferential and radial direction of the wheel, and preferably projecting in opposite radial directions from a ring along which they are staggered in circumferential direction. The slant of the armature portions to the plane of oscillation and to the path of oscillation are selected so that during the rotation of the wheel, alternately the magnetic coupling force between one of two magnets with their respective cooperating armature portion prevails. During each stroke in one direction, one of the magnets is effective to drive the wheel, and the other magnet is ineffective. During the reverse stroke, the magnetic coupling is reversed. Due to the different width of the air gaps, the force produced by the respective non-effective magnet is comparatively low.

Advantageously, the two magnets are arranged on the oscillatory means at a distance along the path which corresponds to the distance of the smallest air gap from the greatest air gap along the respective armature portion. The armature portions have between the region of the greatest and smallest air gaps, effective drive portions which are slanted to the path of oscillations, and, when coupled with the respective magnet, produce a turning moment on the wheel.

The wheel can be constructed so that it is shifted one or two steps for each oscillation, and the shifting of the wheel may take place in the region of the reversing points of oscillation, or in the region of the center of the oscillation. It is particularly advantageous to arrange the slanted part of the armature portions in such a manner that the shifting of the wheel takes place when the oscillatory magnet moves through the zero position at the center of the oscillation path. In this event, the oscillatory means has the greatest kinetic energy during switching from one armature portion to the other. In order to obtain in such an arrangement a reliable shifting function even if the oscillation amplitude is different, it is advantageous to extend the ends of the armature portions in the direction of the path of the magnet or magnets so that the magnet is guided before and after arriving at the reversal points without any shifting action on the wheel, until the magnet arrives at the center part of the respective armature portion which is slanted to the plane of oscillations so that a magnetic torque is produced.

When the two armature portions, which cooperate with two magnets, project in opposite substantially radial di-

rections from a connecting ring, the inner and outer armature portions are slanted to the path of oscillation at different angles, and are staggered in circumferential direction. The greatest gap is provided in the region of the connecting ring. The inner and outer ends of the armature portions preferably extend in the direction of the path of oscillation of the magnets for stabilizing the amplitude of oscillation.

The influencing of the magnetic coupling between the magnets and the armature portions by variations of the air gap, can be further improved by using armature portions whose width and thickness varies, for example, the width of the armature portions decreases from the region of the smallest air gap to the region of the greatest air gap.

15 A wheel according to the invention can be manufactured in a simple manner by punching or etching, or in other manners, of temporarily magnetizable material such as soft iron, which is transversely stamped and deformed to saw tooth shape, so as to be slanted to the plane of oscillation. U-shaped or V-shaped impressions may be stamped into the armature portions.

20 The oscillatory means which carries the magnet or magnets, preferably oscillates angularly about an axis which is parallel to the axis of the wheel. However, a leaf-spring oscillator or a tuning fork oscillator can also be used which is provided in suitable manner with permanent magnet means,

25 The device of the invention can advantageously be used for a clock or watch, particularly with a transistor controlled clockwork in which the oscillatory magnet controls the step of the wheel in the manner of the balance wheel. In this event, additional control magnets form part of the oscillatory means, which are controlled in a known manner by an electrically energized coil arrangement. A 30 control magnet induces in a control coil a pulse, which opens or closes a control transistor which is provided in the circuit of a drive coil whose field produces a drive torque acting on the oscillatory means which is restrained by a spring. The device of the invention may also be used for magnetically controlling the escapement mechanism of a spring driven watch or clock.

35 The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawings.

50 BRIEF DESCRIPTION OF THE DRAWING

FIG. 1 is a fragmentary side elevation illustrating a first embodiment of the invention;

55 FIG. 2 is a fragmentary plan view of the embodiment of FIG. 1;

FIG. 3 is a front elevation of the embodiment of FIGS. 1 and 2;

FIG. 4 is a plan view illustrating a driven wheel used in the embodiment of FIGS. 1-3 on a larger scale;

60 FIG. 5 is a front view of the wheel of FIG. 4;

FIG. 6 is a developed view illustrating a peripheral armature portion of the wheel of FIGS. 4 and 5;

FIGS. 7, 8, 9 and 10 are fragmentary plan views illustrating a second embodiment of the invention in successive operational positions; and

65 FIG. 11 is a cross-sectional view taken on line A-B in FIG. 7.

70 DESCRIPTION OF THE PREFERRED EMBODIMENTS

Referring first to the embodiment of FIGS. 1-6, an oscillatory means is mounted on a pair of support plates 1 and 2 for oscillatory movement about the axis of a shaft 3. The oscillatory means further include two carrier

plates 4 and 5 secured to shaft 3. Carrier plate 4 supports a drive magnet 9 at one end, and a control magnet 7 at the other end. A corresponding control magnet 8 is secured to carrier plate 5 opposite control magnet 7. A coil spring 3 is secured at one end to the hub of carrier plate 4, and at the other end to a lug on supporting plate 1, and applies a torque to the oscillatory means 3, 4, 5, 7, 8, 9 acting in one direction of oscillation.

Support plates 1 and 2 further mount a shaft 10 which carries the driven wheel 11. The wheel is stepwise rotated in one direction, as will be described hereinafter in greater detail, so that shaft 10 is driven and drives through a worm 12 and a worm gear 13, the movable wheels of a clockwork, not shown.

An inertia wheel 14 is mounted for rotation on a flange 15 of shaft 10, and is frictionally connected with the same.

Coil means 16 which may consist of drive coils, and control coils wound bifilar, coaxial or disk shaped, produce together with the control and drive magnets 7 and 8 magnetic field pulses which oscillate the oscillatory means at a frequency between 15 and 40 hertz, and at an amplitude between 10° and 30°. During this oscillation, magnet 9 moves along a part-circular path, illustrated in FIG. 2 by double arrow *a*.

Magnet 9 cooperates with and drives, a wheel 11 which is preferably stamped in one piece out of a temporarily magnetizable material. Wheel 11 has a hub portion 11c from which spokes 11d outwardly project at an angle to the respective radial vector. Each spoke 11d is integral with an armature portion 11a which is connected at its outer end by an armature portion 11e with the armature portion 11b, whose inner end is secured to the inner end of the respective following armature portion 11a. In this manner, the three armature portions 11a, 11b and 11e form an annular zig-zag shaped armature structure around the periphery of the wheel.

FIGS. 4 and 6 show the relative angular positions of the armature portions 11a, 11b and 11e in relation to the path *a'* along which the armature portions magnetically cooperate with the oscillating magnet 9. Due to the slant of armature portions 11a and 11b to the plane of oscillation in which the path *a'* is located, the air gap between magnet 9 and armature portions 11a and 11b, respectively, increases during each oscillatory stroke of magnet 9 so that the magnetic coupling force is reduced until magnet 9 arrives at the respective reversing point where the short, connecting armature portion 11e is located, which is inclined at a steep angle to the plane of oscillation *a'*, and which is positioned to suddenly reduce the width of the air gap so that the oscillatory magnet always drives wheel 11 in the same direction of rotation.

Referring now to the embodiment of FIGS. 7 to 11, an oscillatory means 17 is partly shown which includes two magnets 19 and 20, swinging in the direction of the double arrow *b* about an axis 18 which is parallel to the axis of the driven wheel 22. Magnets 19 and 20 are spaced along the circular path along which they move in the direction *c* or *d*.

The wheel 22 has inner armature portions 24 and outer armature portions 25. The inner ends of the inner armature portions 24 are connected with the central hub portion of wheel 22, and the outer ends of armature portions 24 and the inner ends of armature portions 25 are connected by a ring 23 so that armature portions 24 are spokes carrying the ring 23 with the outer armature portions 25. The inner armature portions 24 and the outer armature portions 25 are constructed in such a manner that the magnetic coupling is switched from an inner armature to an outer armature portions, and from an outer armature portion to an inner armature portion in the central neutral position of the oscillatory means 17 with magnets 19 and 20 which has constructive and kinematic advantages since the oscillatory means 17 has the greatest kinetic energy when moving through the neutral central position.

The outer armature portions 25 have an inner end portion 25a, a slanted central part 25b, and an outer, radial end portion 25c. The axis 18 and the path of oscillation of magnets 19 and 20 is selected so that magnets 5 19 and 20 move substantially in radial direction of wheel 22 along a tangent on the curved path of magnets 19 and 20 being located in a radial plane passing through the center of wheel 22. Consequently, the part circular path of the magnets 19, 20 is perpendicular to the ring 23.

10 The inner armature portions 24 have two parts 24a and 24b which are slanted different angles in relation to the path of magnet 19. The inner part 24a of the respective inner armature portions 24 which cooperates with magnet 19, is located in the path of movement of magnet 19, as best seen in FIGS. 8 and 9. The part 24 of the respective operative inner armature portion 24 is slanted to the path.

15 As shown in FIG. 11, the armature portions 24, 25 are also deformed to be partially slanted to the plane in which magnets 19 and 20 oscillate about the axis 18. The air gap between the end face of magnet 20 and the part 25a of armature portions 25 increases during movement of magnet 20, and the air gap between part 24b of armature portion 24 and magnet 19 increases in the opposite 20 direction.

25 Near the end position of the oscillatory means 17, shown in FIG. 7, magnet 20 is magnetically coupled with the outer end part 25c of an outer armature portion 25. When the oscillatory means moves in the direction of 30 the arrows *c*, magnet 20 cooperates with a slanted middle part 25b, attracting the same by a magnetic coupling force so that wheel 22 is turned a step in clockwise direction. When magnet 20 is in the region of the ring 23 and part 25a, the air gap is the greatest, and the magnetic 35 coupling between magnet 20 and parts 25a, 23 can be interrupted.

30 In the following position shown in FIG. 8, magnet means 19, 20 approach the other end position shown in FIG. 9. In the position of FIG. 8, magnet 20 cooperates with ring 23 and with inner part 25a of armature portion 40 25 over a large air gap, while magnet 19 is magnetically coupled with part 24a of the next following inner armature portion 24' due to the small air gap in this region. Thereupon, magnet 19 moves to the end position of FIG. 45 9 along the inner portion 24a of the respective inner armature portion 24' out of the position of FIG. 8. When the oscillatory means 17 swings back from the end position shown in FIG. 9 in the direction of the arrow *d*, at first no turning moment is applied to the wheel 22, since 50 magnets 19 and 20 move in the directions of the inner parts 24a and 25a of the respective inner and outer armature portions 24' and 25'. During continued movement toward the other end position shown in FIG. 10, the magnetic coupling between magnet 20 and armature portion 55 25' is interrupted while magnet 19 turns wheel 22 in clockwise direction while being magnetically coupled with the part 24b of armature portion 24'. Due to the angular displacement of wheel 22, magnet 20 is now in the region of the outer part 25c of the next following outer armature portion 25, and is magnetically coupled with the 60 same due to the fact that the air gap is small in this region. Magnet 19, however, is now in the region of the greatest air gap with ring 23, so that the following angular displacement of the wheel 22 by the action of magnet 20 65 65 interrupts the magnetic coupling between magnet 19 and armature portion 24'. The position of FIG. 10 corresponds to the position of FIG. 7 after turning wheel 22 in an angular step so that the above-described operations can be repeated for rotating wheel 22 under the control of the oscillating magnet means 19, 20.

70 It will be understood that each of the elements described above, or two or more together, may also find a useful application in other types of magnetic devices for transforming oscillatory motion into rotary motion, differing from the types described above.

While the invention has been illustrated and described as embodied in oscillating magnet means cooperating through varying air gaps with armature portions of a wheel for rotating the same, it is not intended to be limited to the details shown since various modifications and structural changes may be made without departing in any way from the spirit of the present invention.

Without further analysis, the foregoing will so fully reveal the gist of the present invention that others can, by applying current knowledge readily adapt it for various applications without omitting features that, from the standpoint of prior art, fairly constitute essential characteristics of the generic or specific aspects of this invention and, therefore, such adaptations should and are intended to be comprehended within the meaning and range of equivalence of the following claims.

What is claimed as new and desired to be protected by Letters Patent is set forth in the appended claims.

We claim:

1. Magnetic device for transforming an oscillatory motion into a rotary motion, comprising, in combination, oscillatory means and including magnetic means swinging in a plane along a path; and a driven wheel having a circumferential row of temporarily magnetizable armature means, said wheel having a plurality of positions in which successive armature means are located in the region of said path defining a first angle with said path whereby the magnetic force between said magnet means and the respective armature means causes stepwise turning of said wheel in one direction of rotation, and defining a second angle with said plane so that during rotation of said wheel in said one direction, a magnetic coupling force between said magnet means and the respective cooperating armature means is established at the beginning of a stroke, decreases during the stroke due to the widening of the air gap, and is interrupted at the end of the stroke whereupon said magnet means magnetically couples with the next following armature means.

2. A device as claimed in claim 1 wherein said oscillatory means has an axis; wherein the axis of said wheel is parallel to said axis of said oscillatory means so that said wheel is located in a plane parallel to said plane of said magnet means except for said armature means which are slanted at said second angle to said plane; and wherein the respective armature means which cooperates with said magnet means is slanted at said first angle to a tangential plane on said path.

3. A device as claimed in claim 1 wherein said wheel has a central portion and a peripheral portion formed by said plurality of armature means; wherein each armature means includes a first armature portion, a second armature portion, and a third armature portion, connecting said first and second armature portions, said first and second armature portions alternately converging in outward and inward radial directions and being connected at the extremities thereof by said third armature portion, said first and second armature portions defining first angles with said path and forming a circular sinusoidal or zig-zag shaped magnetizable structure about said central portion; wherein said first and second armature portions are slanted at second angles to said plane between the reversing points of the swinging motion of said magnet means along said path; and wherein said third armature portion is steeply inclined to said plane and is slanted to the same in a direction opposite to the slant of said first and second armature portions to said plane.

4. A device as claimed in claim 3 wherein said central portion of said wheel includes a hub portion and a plurality of spoke portions having outer ends connected with the inner ends of said first armature portions and being spaced from said path and said plane so that no substantial magnetic force is applied by said magnet means to said spoke portions.

5. A device as claimed in claim 1 wherein each arma-

ture means includes an inner armature portion and an outer armature portion oppositely slanted at first angles to said path; wherein said magnet means is movable along a part-circular path and includes outer and inner magnets spaced in the direction of said path and magnetically cooperating with said outer and inner armature portions, respectively, said outer and inner armature portions being slanted at opposite second angles to said plane so that during a stroke of said oscillatory means with said magnets in one direction the magnetic force exerted by said outer magnet on said outer armature portions turns said wheel one step in said one direction of rotation while said inner magnet is ineffective, due to the width of the respective air gap, and so that during a stroke in the opposite direction, the magnetic force exerted by said inner magnet on said inner armature portions turns said wheel one step in the same direction of rotation, while said outer magnet is ineffective due to the width of the respective air gap.

6. A device as defined in claim 5 wherein said outer and inner magnets are mounted on said oscillatory means at a distance in the direction of said path which is substantially the distance between the smallest part and the widest part of the air gaps between said magnets and said armature means; and wherein said outer and inner armature portions have between said smallest and widest parts of said air gaps, central parts slanted to said path and said plane.

7. A device as claimed in claim 6 wherein said slanted central parts of said inner and outer armature portions are disposed in the middle of said path; and wherein each of said armature portions has two end portions at opposite ends of said central part which extend in the direction of said path when the respective armature portion magnetically cooperates with the respective magnet.

8. A device as claimed in claim 7 wherein said wheel has an axis of rotation parallel with said axis of said oscillatory means, a hub part from which said inner armature portions outwardly project, a ring concentric with said axis and secured to the outer ends of said inner armature portions, and to the inner ends of said outer armature portions, said outer and inner armature portions being staggered in circumferential direction along said ring.

9. A device as claimed in claim 8 wherein the air gaps between said outer magnets and outer armature portions, and also between said inner magnets and said inner armature portions are widest in the region of said ring.

10. A device as claimed in claim 9 wherein the width of said armature portions decreases from the region where the air gap is smallest to the region of the widest air gap near said ring for reducing the magnetic force.

11. A device as claimed in claim 7 wherein said wheel and said armature portions are made of magnetizable sheet material, and wherein said central parts of said armature portions are deformed out of the plane of said sheet material so as to be slanted to said plane in which said magnet means oscillates.

12. A device as claimed in claim 1 wherein said oscillatory means has an axis in its central region and said magnet means at one end, and includes control magnet means located at the other end thereof; and comprising elastically energizable coil means cooperating with said control magnet means for causing oscillation of said oscillatory means for rotating said wheel for driving a clockwork.

13. A device as claimed in claim 1 wherein said magnet means is a single magnet; wherein each armature means includes two armature portions slanted at opposite angles to said path, and being slanted to each other; and wherein said magnet moves along one of said armature portions during a stroke in one direction, and along the other armature portion during a stroke in the opposite direction.

14. A device as claimed in claim 1 wherein said magnet means includes two magnets spaced in the direction of said path; wherein each armature means includes two armature portions spaced in circumferential and radial directions of said wheel; and wherein said magnets move along said two armature portions, respectively, of one armature means during each stroke in one direction and along said two armature portions of the next following armature means during the following stroke in the opposite direction.
